UNITED STATES PATENT OFFICE.

SAMUEL HEIMBERG, OF NEW YORK, N. Y.

DESIGN FOR A TOBACCO-PIPE.

42,939.

Specification for Design.

Patented Aug. 27, 1912.

Application filed May 20, 1912. Serial No. 698,638. Term of patent 7 years.

To all whom it may concern:

Be it known that I, SAMUEL HEIMBERG, a subject of Austria, residing at New York, in the county of Kings and State of New York, have invented a new, original, and ornamental Design for a Tobacco-Pipe, of which the following is a specification, reference being had to the accompanying drawing, forming part thereof.

Figure 1 is a side view of a tobacco pipe,

showing my new design; and Fig. 2 is a top view of the same.

I claim:

The ornamental design for a tobacco pipe, as shown.

SAMUEL HEIMBERG.

Witnesses:

ABRAHAM ROSEN,
MAX HURWITZ.
